PREPARATION OF ZINC PROPIONATE

Arthur George Weber, Wilmington, and Clement H. Hamblet, Gordon Heights, Del., assignors to E. I. du Pont de Nemours & Company, Wilmington, Del., a corporation of Delaware

No Drawing. Application November 30, 1945.
Serial No. 632,082

4 Claims. (Cl. 260—429)

1

This invention relates to a process for the preparation of zinc salts of organic acids and more particularly to the preparation of zinc propionate.

Various methods have been proposed for the preparation of the zinc salts of the organic acids such, for example, as the reaction of the organic acid with a heavy metal carbonate or by the exposure of the metal to the warm vapors of the organic acids, the latter procedure being employed for the preparation of white lead, requiring many days and in some cases weeks in processing. These slow and tedious processes are unsuitable for rapid economical formation of the zinc salts of organic acids.

An object of the present invention is to provide a process for the preparation of zinc salts of organic acids. Another object of the invention is to provide a process wherein organic acids can be converted to the corresponding zinc salt by direct contact with the metal. A further object of the invention is to provide a process wherein propionic acid is converted to its zinc salt by direct reaction of the acid with zinc in the presence of oxygen. Other objects and advantages of the invention will hereinafter appear.

The above objects are accomplished in accord with the broadest aspects of the invention by a process wherein an organic acid such as propionic acid is heated with zinc while in contact with oxygen. More specifically, the process may be conducted by passing an oxygen-containing gas such as air and the organic acid into a converter charged with metal pellets, gas and acid flowing cocurrent or countercurrent through the converter. By this process it has been found possible not only to increase the reaction rate of the formation of zinc propionate from propionic 300% over a process using no oxygen, but the superficial surface attack of the acid in the absence of oxygen is replaced by a penetrating thorough disintegration and conversion of the zinc particles to the salt.

The temperature of the reaction may vary through wide limits according to the nature of the organic acid used, the unsaturated acids being preferably reacted at a lower temperature than the saturated acids to inhibit degradation. When normally solid acids are treated they should be heated at least to that temperature at which they are fluid in order that the oxygen or oxygen-containing gas can be easily bubbled through them. Generally speaking, however, temperatures may range between 50 and 200° C. and more specifically for the fatty acids, tempera-

2

tures ranging between 70 and 150° C. with a preferred range for the preparation of zinc propionate between 100 and 120° C. Atmospheric or superatmospheric pressures may be used if desired.

The process of the invention is adapted to the preparation of zinc salts from an organic acid containing not more than six carbon atoms or mixture thereof. As examples of the organic acids that may be employed in accord with the process of the invention are: the fatty acids; acetic, propionic, butyric, and valeric acid; hydroxy acids such, for example, as glycolic acid, lactic acid, and tartaric acid; as well as polycarboxylic acids such, for example, as oxalic acid, glutaric acid and adipic acid; and the unsaturated acids such, for example, as acrylic acid, and methacrylic acid, as well as the aromatic acids such, for example, as benzoic acid.

20 The process may be carried out by a continuous or discontinuous procedure. The former may, for example, be illustrated by the use of a converter, of relatively great length to width, disposed in a vertical position and charged with 25 zinc which may be in the form of moss, chips, flakes, or metal pellets of a suitable diameter such as, for example, from $\frac{1}{8}$ to $\frac{1}{2}$ inch. If a water soluble organic acid higher than acetic is to be converted to the zinc salt it is introduced 30 in an aqueous solution into the converter together with an oxygen containing gas such as air and the reaction within the converter maintained at the optimum temperature for the particular type of acid being converted. When carried out in 35 this, the preferred manner, the acid or acid and water may be introduced at the top of the converter and the product collected from the bottom while air is permitted to bubble up through the descending acid and the process thereby conducted under countercurrent flow conditions, the 40 spent air being allowed to issue from the top of the converter carrying with it the water formed during the reaction. Contrariwise, both acid and air can be introduced into the bottom of the converter to give cocurrent flow, the product as well 45 as the spent air and water formed issuing from the top of the converter. To enhance the flow of fluids within the converter, which increases the speed of the reaction, a portion of the reactants may be pumped from the top of the converter and reintroduced into the bottom thereof, the 50 velocity and turbulence of the flow within the converter being regulated in part by the amount and degree of this recycled material. As will be 55 appreciated by those skilled in the art, the re-

cycling may be conducted in the reverse order, that is by taking the product from the bottom and reintroducing it into the top of the converter, although the reverse is the preferred method, and a further modification may be effected by removing the product from intermediate positions to the converter. If desired, the throughput of acid may be adjusted to the length of the converter in order that substantially all of the acid is converted to its salt as it emerges from the converter.

The process may likewise be conducted batchwise which may be effected by charging a converter such as that described above or any suitable vessel with the metal particles and the acid to be reacted; the acid is raised to reaction temperature and the reaction continued until all of the acid has been converted to the salt whereupon it is discharged from the converter. Throughout the reaction air or oxygen or an oxygen-containing gas is bubbled through or otherwise dispersed into the liquid. During batchwise processing it is likewise desirable to recirculate the reactants which may be accomplished by an outside circuit provided with a suitable pump whereby the reactants are removed and returned to the vessel in order to maintain a constant, preferably turbulent, flow within the vessel.

When a converter of greater length than width is employed, a non-homogeneous liquid mixture is sometimes formed in the converter. Relatively water-insoluble acids or their salts which are relatively water-insoluble are responsible for this lack of homogeneity. Since the acid is generally lighter than the water, the latter tends to collect in the bottom of the converter during the initial stages of the reaction. As the reaction proceeds and the zinc salt increases in concentration in the converter the positions of water and acid and product in the converter are reversed. Unfortunately, this reversal in position takes place rapidly with a vaporization of an appreciable part of the water with the result that unless due precautions are taken a large part of the charge will be blown from the top of the converter.

It has been found that the above disadvantageous result can be eliminated by recycling some of the material from the converter through an external separator. This method inhibits the settling of large amounts of water during the initial stages of the reaction and thereby renders it possible to conduct the reaction without loss of products from this cause.

The reaction of an organic acid with zinc is exothermic and consequently after the reaction has been initiated no further heat input is required but on the contrary it is usually desirable to provide means for withdrawing the heat of reaction in order to maintain the temperature within proper bounds. Some of the heat of the reaction is absorbed by the water discharged with the spent gas from the converter, another portion by the sensible heat in the spent gases but it has been found that in addition to these heat controlling means it is often desirable to introduce water into the converter and utilize its sensible and latent heat to control the reaction within the preferred temperature range.

As has been indicated the process is applicable to the conversion of any organic acid to its zinc salt. Inasmuch as some zinc salts are soluble in a liquid consisting of the acid portion of the salt while others are not, a different procedure is recommended when zinc salts of different types

are to be made. When the zinc salt is soluble in the acid of which it made the temperature of the reaction is maintained above the transition point of the mixture, if a batchwise or continuous process is to be conducted. In some cases, the solution of acid and salt can be withdrawn from the converter, cooled down to precipitate the salt, the salt separated by filtration and the acid returned to the converter. Analogous to the latter type of procedure is that used for the preparation of salts which are relatively insoluble in the acid such as zinc propionate. Under such circumstances it is usually desirable to effect the reaction in a mutual solvent for the acid and salt (in the case of zinc propionate this solvent is water) from which the salt can be crystallized or otherwise separated after withdrawing it from the reaction converter, the unreacted acid being returned to the reaction.

The use of a solvent may be illustrated by the preparation of zinc propionate wherein an aqueous solution containing 80% propionic acid or less together with air is passed through a converter containing zinc; the product issuing from the converter is passed into a cooling and crystallizing chamber, the crystals of zinc propionate separated and the aqueous solution of propionic acid returned to the converter with make-up acid preferably after removal of water of reaction.

The examples illustrate embodiments of the invention in which parts are by weight and to which the invention is not to be limited.

Example 1.—A column having a height to diameter ratio of 40.1 was charged with 429.6 parts of mossy zinc and 316.0 parts of propionic acid. Air was passed upward through this mixture for a period of 110 minutes at a space velocity of 34.5, the reaction mixture being maintained at 143–145° C. by external temperature controls. The product obtained was crystallized at 0° C. and filtered, giving a crystalline crop which after drying was found to contain 31.2% zinc (theory for zinc propionate—30.9% zinc).

Example 2.—A column having a height to diameter ratio of 28.1 was similarly charged with 395.0 parts of mossy zinc and 178.0 parts of a 75% solution of propionic acid in water. Nitrogen was passed upward through this mixture for a period of 70 minutes at a space velocity of 9, the reacting mixture being maintained at 129–130° C. The small amount of zinc propionate recovered from the product corresponded to a production rate of only 3.5#/cu. ft./hr.

Example 3.—When a charge similar to that described in Example 2 was treated in a column similar to that described in Example 2 at 129–130 C. with oxygen at a space velocity of 11, a copious yield of zinc propionate was obtained in 55 minutes, average production rate corresponding to 11.3#/cu. ft./hr.

As shown by the examples, the rate of oxygen flow may be varied and it has been found that this variation may range between a space velocity of 1 and 100, space velocity being defined as the unit volume of air passing per hour per superficial volume occupied by the metal particles in the tower, the fluid volumes being determined under standard temperature and pressure conditions. While the examples have described the use of air and oxygen, inert gas-oxygen mixtures may be employed.

The use of an antioxidant is highly advantageous when unsaturated organic acids are converted to their zinc salts. The evolution of carbon dioxide indicates degradation of the acid or

salt during the reaction and it has been found that the presence of an antioxidant inhibits and usually entirely eliminates this degradation. Suitable examples of antioxidants which may be employed are, in addition to the hydroquinone described in the examples, pyrogallol, phenol, phenyl-alpha-naphthyl amine, mesitols, and other suitable antioxidants. The antioxidant may be used in amounts ranging between 0.005 and 2% of the organic acid by weight with a preferred range particularly for hydroquinone between 0.01 and 0.02.

We claim:

1. A continuous process for the preparation of zinc propionate by reacting propionic acid with metallic zinc which comprises reacting metallic zinc with an aqueous solution of propionic acid at a temperature between 50° and 200° C. while continuously during the reaction passing air through the reacting mixture the reaction being conducted by passing the reactants continuously into and the products continuously out of the reaction zone.
2. The process of claim 1 conducted with an air space velocity between 1 and 100.
3. The process of claim 1 conducted at a temperature between 70° and 150° C. and with an air space velocity between 1 and 100.
4. A process for the preparation of zinc propionate from propionic acid and metallic zinc

10

15

20

25

30

which comprises passing at a temperature between 70 and 150° C. a 75% aqueous solution of propionic acid over mossy zinc while bubbling air through the solution throughout the reaction, the reaction being conducted by passing the reactants continuously into and the products continuously out of the reaction zone.

Certificate of Correction

Patent No. 2,452,003.

October 19, 1948.

ARTHUR GEORGE WEBER ET AL.

It is hereby certified that errors appear in the printed specification of the above numbered patent requiring correction as follows:

Column 4, line 34, Example 1, for "40.1" read *40:1*; line 45, Example 2, for "28.1" read *28:1*;

and that the said Letters Patent should be read with these corrections therein that the same may conform to the record of the case in the Patent Office.

Signed and sealed this 25th day of January, A. D. 1949.

[SEAL]

THOMAS F. MURPHY,
Assistant Commissioner of Patents.
